UNITED STATES PATENT OFFICE

140,582

DESIGN FOR A ROUND-THE-NECK MIRROR

Samuel J. Winslow, Providence, R. I.

Application December 16, 1944, Serial No. 116,929

Term of patent 7 years

(Cl. D86—2)

To all whom it may concern:

Be it known that I, Samuel J. Winslow, a citizen of the United States, residing at Providence, in the county of Providence and State of Rhode Island, have invented a new, original, and ornamental Design for Round-the-Neck Mirrors, of which the following is a specification, reference being had to the accompanying drawing, forming part thereof.

In the drawing,

Fig. 1 is a front elevational view of a round-the-neck mirror showing my new design with the support in its closed position;

Fig. 2 is a side elevation thereof; and

Fig. 3 is a perspective view thereof on a slightly reduced scale with the mirror in its supported position.

The back of the mirror is the same as the front of the mirror as there are two mirror glasses back to back.

I claim:

The ornamental design for a round-the-neck mirror, as shown and described.

SAMUEL J. WINSLOW.
